UNITED STATES PATENT OFFICE.

FRANCIS SCHENKER, OF WALLINGFORD, CONNECTICUT, ASSIGNOR TO DOWD-RODGERS COMPANY, OF WALLINGFORD, CONNECTICUT, A CORPORATION OF CONNECTICUT.

DESIGN FOR A UNITARY COMBINATION TRAY AND CONDIMENTS HOLDER.

Application filed March 22, 1924. Serial No. 9,040. Term of patent 3½ years.

To all whom it may concern:

Be it known that I, FRANCIS SCHENKER, a citizen of the United States, residing at Wallingford, in the county of New Haven and State of Connecticut, have invented a new, original, and ornamental Design for a Unitary Combination Tray and Condiment Holders, of which the following is a specification, reference being had to the accompanying drawing, forming part thereof.

The figure is a perspective view of a unitary combination tray and condiment holders, showing my new design.

I claim:

The ornamental design for a unitary combination tray and condiment holders, as shown.

FRANCIS SCHENKER.
